LUGGAGE CART WITH CHILD SEAT

James M. Muellner, 1777 Stillwater St.,
White Bear Lake, Minn. 55110

Filed Feb. 2, 1972, Ser. No. 223,059

Term of patent 14 years

Int. Cl. D12—02

U.S. Cl. D12—22

Fig. 1

Fig. 2

Fig. 3

FIG. 1 is a front perspective view of a luggage cart with child seat showing my new design;

FIG. 2 is a rear perspective view thereof; and

FIG. 3 is a right side elevational view thereof.

The undisclosed bottom is substantially plain and unornamented.

I claim:

The ornamental design for a luggage cart with child seat, as shown and described.
